UNITED STATES PATENT OFFICE.

GEORGE GREGORY SMITH, OF FLORENCE, ITALY.

CALCIUM-CARBID CARTRIDGE.

SPECIFICATION forming part of Letters Patent No. 660,170, dated October 23, 1900.

Original application filed December 8, 1899, Serial No. 739,628. Divided and this application filed May 17, 1900. Serial No. 17,054. (No model.)

To all whom it may concern:

Be it known that I, GEORGE GREGORY SMITH, lawyer, a citizen of the United States, residing at Villa Bel Riposo, San Domenico, 5 Florence, Italy, have invented certain new and useful Improvements in Tins or Cans for Calcium Carbide, of which the following is a full, clear, and exact description.

The present invention relates to tins or cans 10 for containing calcium carbide for generating acetylene gas; and the object of the invention is to provide a tin or can which will not burst when water is fed to the carbide therein for the purpose of generating the gas. It is well known that the ordinary cans burst under 15 these circumstances, owing to the rapid development of the gas and the consequent expansion of the carbide. When these cans burst, the residual products formed are free 20 to pass into the generating apparatus and stop up the pipes and valves and create many other disadvantages. It is therefore essential that these products remain shut up in the can, so that they may be removed entirely 25 out of the apparatus with the exhausted can.

The object of the invention is attained by placing within the can and approximately in 30 the center of the carbide therein a tube having perforated walls and extending approxi- 35 mately from the top to the bottom of the can. The longitudinal edges of the piece of metal forming the tube are not fastened together, but simply laid one over the other, and the interior of the tube is left empty, the carbide 40 in the can occupying the annular space between the interior of the walls of the can and the exterior of the tube. The tube is perforated along its whole length and may or may not be fastened within the can, since if not fastened at the top or bottom it will be supported in position by the carbide around it.

In order to render the present specification 45 easily intelligible, reference is had to the accompanying drawings, in which similar letters of reference denote similar parts throughout both views.

Figure 1 is a vertical section through a can constructed according to the present invention, and Fig. 2 is a sectional plan of the same.

Within the can *a* and approximately down 50 the longitudinal center of the same the perforated tube *b* is arranged, having its longitudinal edges simply laid one over the other, as will be clearly seen from Fig. 2.

The can is punctured at the top and bottom 55 at a point within the cross-sectional area of the tube and the water entering will thus have free access to every part of the carbide at once. The carbide expanding will not burst the tin or can, as has hitherto generally been 60 the case, but will compress the tube and leave the exterior walls of the can intact.

For the purpose of holding the tube *b* in a central position radial arms *c*, having downwardly-flanged ends *c'* *c''*, are secured to the 65 inner wall of the can adjacent to the top thereof, and similar radially-disposed arms *d*, having vertical flanges *d'* *d''*, are secured to the inner wall of the can adjacent to the bottom thereof. The flanges *c'* *d'* of these arms 70 are secured to the can by solder or otherwise, and the flanges *c''* *d''* act to guide the tube *b* as it is inserted in the can and to retain it centrally thereof.

One of the most important advantages of 75 the present construction is that the perforated tube enables the water to circulate freely to all parts of the carbide at once, whereas in punctured cans having no tube the water only meets the carbide just at the puncture, gas is rapidly developed at this point, and the residual products will partially stop 80 the progress of the water to the other parts of the carbide, rendering the development of gas very slow and in some cases almost entirely stopping the generation of gas.

I claim as my invention—

1. In combination with a receptacle for containing calcium carbide, a perforated tube located in said receptacle and having free longitudinal overlapping edges.

2. In combination with a receptacle for con-

taining calcium carbide, guides secured to the inner wall of said receptacle; and a perforated tube having free longitudinal overlapping edges inserted between said guides.

- 5 3. In combination with a receptacle for containing calcium carbide, radial arms secured to the inner wall of said receptacle adjacent to the top and bottom thereof, said arms having guiding-flanges; and a perforated tube

having free longitudinal overlapping edges 10 inserted between said guiding-flanges.

In witness whereof I have hereunto set my hand in presence of two witnesses.

GEORGE GREGORY SMITH.
